Brown & Hall.

UNITED STATES PATENT OFFICE.

WILLIAM R. PITTS, OF BROOKLYN, NEW YORK.

WIRE MAT.

SPECIFICATION forming part of Letters Patent No. 378,214, dated February 21, 1883.

Application filed February 23, 1887. Serial No. 228,495. (No model.)

To all whom it may concern:

Be it known that I, WILLIAM R. PITTS, of Brooklyn, in the county of Kings and State of New York, have invented a new and useful 5 Improvement in Wire Mats, of which the following is a specification.

My invention relates to mats which are composed of a body fabric formed of connected coils of wire and a frame surrounding the mat, 10 and with which the coils are connected and by which the fabric formed of interlaced coils is held in flat extended condition.

The invention consists in a mat having a body fabric of interlaced wire coils extending 15 parallel with each other and with the opposite side edges or margins of the mat, and having its coils at their points of interlaced contact united by solder, and a frame surrounding and embracing the body fabric, and serving 20 to prevent deflection and the consequent breaking of the solder at the points of connection.

The invention also consists in a mat composed of a body fabric of connected wire coils 25 extending parallel with each other and with the opposite edges or margins of the mat, and a frame comprising metal side bars or portions having greater transverse section than the wire of which the coils are formed, and which 30 extend through the side coils parallel with their axes, and are embraced by the regular convolutions of the side coils, and end bars or portions to which the ends of the coils are secured. In my above combination I prefer to 35 form the end bars double—that is to say, of two parallel members or portions, between which the end portions of the coils are clamped—and both parts or portions of said end bars are of 40 no greater depth than the thickness of the mat.

In the accompanying drawings, Figure 1 represents in plan view a portion of a mat embodying my invention, and in which the frame is composed of a bent bar half-oval in 45 transverse section. Fig. 2 is a sectional view of a portion of the mat on the plane of the dotted line $x-x$, Fig. 1. Fig. 3 is a transverse section upon the plane of the dotted line $y-y$, Fig. 1; and Figs. 4 and 5 are views similar to Figs. 50 1 and 2 of a portion of a mat in which the frame is formed of a flat bar bent to the desired shape.

Similar letters of reference designate corresponding parts in all the figures.

The body fabric A of the mat is composed 55 of coils of wire which extend parallel with each other and with opposite edges or margins of the mat, and which are connected together; and in this example of my invention the connection of the coils is formed by interlacing 60 them one into the other, as shown at the points b. As many of the coils as are necessary are thus interlaced or connected, so as to form a body fabric of the desired size, and the body fabric is sustained and held in shape by a frame 65 which surrounds the mat.

In Figs. 1, 2, and 3 I have represented a frame formed by bending a bar of half-oval transverse section much greater than the size of the wire employed in making the coils to 70 produce parallel side portions, B, and end portions, B', one only of which is here shown in the drawings. The side bars or portions, B, extend through the coils A at opposite edges or margins of the mat parallel with the axes 75 of such coils, and are embraced by the regular convolutions of such coils, and the end bars or portions, B', serve to hold the side bars or portions, B, at proper distances apart and have secured to them the ends of the several 80 coils. In this example of my invention I employ at each end of the mat a bar or strip, B², which is passed through the end convolutions of the several coils, and which is bound to the end bar or portion, B', by bands of wire c, or 85 other means, the ends of the coils being clamped between the members B' B², of which the end bars are composed. It will therefore be seen that the end bars or portions of the frame are double or composed each of two parallel members, 90 between which the ends of the several coils are clamped.

The double end bars formed by two parallel members or portions are, when combined, of no greater depth than the thickness of the mat, 95 and hence when placed upon a floor or other support the mat will have a resting surface on the floor or other support throughout its extent.

For greater strength, I prefer to make the 100 parallel coils C which are at opposite longitudinal edges of the mat each of two or more wires, which extend parallel with each other throughout the several convolutions of the

coils, thereby forming at each side of the mat a multiple coil, through which the side bar or portion, B, of the frame extends parallel with the axes of such multiple coil.

5 The body fabric of wire coils is dipped in a galvanizing-bath, or has its points of interlaced engagement soldered, and the frame serves to hold the body fabric in a flat state and prevent deflection thereof and consequent 10 breakage of these soldered connections.

In the example of my invention shown in Figs. 4 and 5 I have represented the side bars or portions, B, of the frame as made separate from the end bar or portion, B', and as bent 15 to overlap the end bar or portion, B', at b'. These side bars or portions, and also the end bar, B', are of metal, having a flat transverse section, and the side bars or portions, B, extend through the edge coils, C, of the body 20 fabric parallel with the axes of such coils, as before described. The end bar or portion, B', is passed through the end convolutions of the several coils, and the ends of the coils are united by twisting, as shown at c, on the out- 25 side of the bar B', or are simply bent over upon the outer side of such bar.

I am aware that ash-sifters and analogous vessels have been woven of wire, and when otherwise completed galvanized, the galvanizing metal serving in a measure to unite the 30 wires at their points of crossing. In such an article, however, the connection of the crossed wires by solder will very soon be broken by the deflection of the article and by blows to 35 which it is subjected. When a mat having a body fabric formed of coils of wire which are connected, and which extend parallel with the side margins or edges of the mat, is surrounded by a frame of sufficient strength to maintain 40 the mat in a flat state and prevent its deflection, the frame renders the mat durable and prevents breakage of the connections formed by solder or by galvanizing metal, such as are produced by galvanizing the mat as a whole. 45 It will be obvious that if the body fabric formed of coils, as described, and soldered at the points of interlacing or intersection, were employed without any frame, the points of soldered union would be very soon broken; 50 but when a substantial frame surrounds such a body fabric and holds it in its flat state and prevents its deflection from a flat plane, it is rendered very durable, and the soldered connections are not as quickly broken as if such a 55 frame were not used.

I am also aware that a bed-bottom has been

formed of interlaced coils extending parallel with each other and with the side edges or margins of the bed-bottom, and to secure such a bed-bottom to a wooden frame a wire of the 60 same size as the wire forming the coils has been passed through the marginal coils and secured at short intervals by staples to the frame of wood. The wire that is passed through the edge coils is not in any sense a frame. It does 65 not sustain the bed-bottom in position, as that office is performed by the rigid frame of wood, and it simply serves as a means through which the coils may be secured to the frame.

What I claim as my invention, and desire to 70 secure by Letters Patent, is—

1. A mat having a body fabric of interlaced wire coils extending parallel with each other and with the opposite side edges or margins of 75 the mat, and having its coils at their points of interlaced contact united by solder, and a frame surrounding and bracing the body fabric, and serving to hold it in its flat state and to prevent deflection and the consequent breaking of the solder at the points of connection, 80 substantially as herein described.

2. A mat composed of a body fabric of connected wire coils extending parallel with each other and with opposite edges or margins of 85 the mat, and a frame formed of side bars or portions, B, extending through the side coils parallel with their axes, and which are embraced by the side coils and are much larger in transverse section than the wire of which the coils are made, and end bars or portions 90 to which the ends of the coils are secured, substantially as herein described.

3. A mat composed of a body fabric of connected wire coils extending parallel with each other and with opposite edges or margins of 95 the mat, and a frame consisting of side bars or portions, B, extending through the side coils parallel with the axes thereof, and which are embraced by the regular convolutions of the side coils, and double end bars between the 100 two parallel members of which the end portions of the coils are secured, and which when the two parallel members are combined are not greater in depth than the thickness of the mat, whereby provision is afforded for the mat 105 to rest throughout its extent upon a flat surface, substantially as herein described.
